DESIGN FOR A HEAD FOR A RETINOSCOPE OR THE LIKE

Charles A. Ellis, Southbridge, Mass., assignor to
American Optical Company, Southbridge,
Mass., a voluntary association of Massachusetts

Application September 11, 1944, Serial No. 115,255

Term of patent 14 years

(CL. D57—1)

To all whom it may concern:

Be it known that I, Charles A. Ellis, a citizen of the United States of America, residing at Southbridge, in the county of Worcester and State of Massachusetts, have invented a new, original, and ornamental Design for a Head for a Retinoscope or the like, of which the following is a specification, reference being made to the accompanying drawing, forming a part thereof.

Fig. 1 is a front elevational view of a head

for a retinoscope or the like embodying my new design;

Fig. 2 is a side elevational view of the head for a retinoscope or the like shown in Fig. 1; and

Fig. 3 is a sectional view taken on line 3—3 of Fig. 1.

I claim:

The ornamental design for a head for a retinoscope or the like, substantially as shown.

CHARLES A. ELLIS.
